UNITED STATES PATENT OFFICE.

CHARLES M. AHLBERG, OF ST. PAUL, MINNESOTA.

LATCH.

1,115,762.

Specification of Letters Patent.

Patented Nov. 3, 1914.

Application filed June 22, 1912. Serial No. 705,197.

To all whom it may concern:

Be it known that I, CHARLES M. AHLBERG, a citizen of the United States, residing at St. Paul, in the county of Ramsey and State of Minnesota, have invented a new and useful Improvement in Latches, of which the following is a specification.

The object of this invention is to provide a latch for doors, gates and other hinged devices which is simple and inexpensive in construction and effective in use.

A further object is to so construct the latch that it will lift the free end of the door into position to register with the door jamb or casing should the hinges of the door through weakness fail to hold the door in registering position.

In the accompanying drawing forming part of this specification, Figure 1 is a perspective of a door hinged in a door frame illustrating my invention applied thereto, and Fig. 2 is a side elevation of a detail showing the invention.

This invention consists of two coöperating elements, one a latch bar A and the other a latch spring or latch bar engaging member B which is adapted to engage the bar A and hold the door C on which the bar is mounted in closed position in its frame D. The member A is formed with a flange 2 on the bar through which screws 3 are passed to secure the bar on the face of the door. The spring B is in the form of a single piece or strip of spring material bent outwardly and upwardly between its ends to form an up and out curved spring shoulder 4 over which the bar passes into engagement during the act of closing the door. The shoulder 4 produces a down curved cup portion 5 into which the bolt is received, the shoulder 4 tending to prevent the bolt from disengaging. The ends of the spring B are secured to the frame D of the door such as by means of screws 6. The door C is shown hung upon spring hinges 7 which tend to close the door in the frame, the springs in the hinges being of sufficient strength to carry the bolt over the shoulder on the latch spring. While the bolt is passing over the

shoulder 4, the latch spring lifts the door 50 sufficiently to register it accurately in the door frame.

In accordance with the patent statutes I have described the principles of operation of my invention together with the apparatus which I now consider to represent the best embodiment thereof but I desire to have it understood that the construction shown is only illustrative and that the invention can be carried out by other means 55 and applied to uses other than those above set forth within the scope of the following claim.

Having described my invention, what I claim as new and desire to protect by Letters Patent is:

A device of the class set forth, comprising, in combination with a door and a door frame in which said door is hinged to close, a latch bar secured to said door and projecting laterally from its free end, and an engaging member on said door frame with which said bar is adapted to engage to hold the door closed, said engaging member consisting of a single strip of spring material 70 secured by its outwardly projecting ends to the door frame and bent upwardly and outwardly between its ends to form a large curved bow, one of which is turned in and down to produce a resilient shoulder over 75 which said bar is adapted to move during the opening and closing of said door, and an indenture at the terminus of said in and down turned portion adjacent to the door frame which forms an engagement by said 80 engaging member with said bar to hold said door in closed position and said spring shoulder being adapted to lift the door during its closing movement to cause the same to register accurately with the opening in 85 the door frame.

In testimony whereof, I have signed my name to this specification, in the presence of two subscribing witnesses.

CHARLES M. AHLBERG.
